D. L. AULD COMPANY, OF COLUMBUS, OHIO, A CORPORATION OF OHIO

NAME PLATE

Application filed December 22, 1928. Serial No. 328,008.

This invention relates to improvements in the method and means of attaching name plates to shells.

It more particularly relates to improvements in the method and means of attaching name plates to radiator shells, and consists in attaching to the name plate discs or plates having struckup therefrom lugs adapted to be inserted through slits in the shell, for the purpose of holding the name plate in engagement with the shell. This is accomplished more particularly by twisting the lug after it has been inserted through the slit in the shell in such a way that the name plate is drawn in close engagement with the shell and held there by the twist on the lug within the shell.

There is shown in the accompanying drawings a preferred embodiment of this method and means, which is shown here by way of illustration.

It is particularly an object of our invention to insure absolutely the proper vertical positioning of the name plate. This is particularly necessary on a horizontal elongated plate or a square plate.

Referring to the drawings:

Figure 1 is a vertical section through the name plate and the shell, showing the lug extending through an ordinary slit in the shell.

Figure 2 is a view similar to Figure 1, but shows the metal of the shell drawn backward and the twisted lug in engagement with the backward-drawn part.

Figures 3 and 4 show a disc attaching means with different forms of lugs.

Figures 5, 6, 7 and 8 show plates having struckup therefrom two lugs part of said figures showing the tips of the lugs having shoulders thereon.

Figures 9 and 10 show a plate with the ends bent up to form lugs.

Figure 11 is a perspective view of one of the discs and the holding lug cut therefrom.

The numeral 1 is used to designate a shell to which the name plate is to be attached. This shell may be the shell of a radiator, or any other body, composed of thin sheet metal. This shell has a slot pierced therein, as indi-

cated by the numeral 2. While in each of Figures 1 and 2 there is shown only one of these slots, yet there may be any number depending upon the size of the plate and the desired security in holding the plate to the shell. If the plate is small one disc 5 may be used for holding the plate to the shell but in case the name plate is long and large two or more discs 5, as shown in Figures 3 and 4, or plates 5' as shown in Figures 5, 6, 7 and 8, may be used.

The name plate is indicated by the numeral 3 and is such a plate as is usually found in automobile radiator shells. As frequently the case in name plates, the name plate here shown has return edges, as indicated by the numeral 4, which tend to hold the body of the plate away from the shell.

As shown in Figures 1 and 2, there is attached to the name plate a disc indicated by the numeral 5. This disc is soldered, or attached to the name plate by other means, and has struckup therefrom an attaching and aligning lug 6. This lug is adapted to be inserted through the slot 2 in the shell, and after being inserted through the slot is twisted, as indicated by the numeral 7, shown in Figures 1 and 2.

When the return edges are large as indicated in Figure 7, the lugs may be formed with shoulders thereon, as indicated by the numeral 8. These shoulders engage the outer surface of the shell while the restricted part extends through the slot in the shell and is twisted to hold the name plate in engagement with the shell. When the return edges are slight, as indicated in Figure 2, the metal part of the shell may be drawn backward at the slot so that when the lug is extended through the slot and twisted, the twist of the lug will be some distance from the point of attachment to the plate. By this means the tendency to rip the plate or disc from the name plate is avoided, the twist being some distance from the point of attachment of the disc or plate to the name plate.

This draw-back part of the shell is indicated by the numeral 9, and is shown in Figure 2. In each of Figures 5, 6, 7 and 8 there are shown plates 5' having struckup there-

from two lugs. These lugs are the same general form and shape as the lugs shown in Figures 3 and 4. These plates 5' may be of any length suitable for the purpose of soldering 5 to the name plate in a manner similar to that of the disc shown in Figures 3 and 4.

Each of these plates 5' may be used alone or in combination with other plates, or with the discs shown in Figures 3 and 4. In Figures 9 and 10 there is shown a modified form 10 of the plate 5" with the ends turned up. These ends may be of the general shape that is shown in Figures 3 and 4 and may have on the ends of the lugs shoulders as indicated 15 in Figure 4, or may be without shoulders, as indicated in Figure 3.

There is shown here a simple and convenient means and method of attaching name plates, and other plates of similar character 20 to shells. The only requirement necessary is that the discs or plates be attached to the name plate, and have struckup therefrom lugs and these lugs be inserted through slots in the shell, and after being inserted through 25 said slots the ends are twisted so as to closely draw the name plate in contact with the shell and hold it in that position.

Whenever it is desired to remove the name plate all that is necessary is that the inner 30 end of the lug be twisted in the direction opposite to that of the original twist so that the lug may be withdrawn from the slot and the name plate removed. This may be done without marring or in any way destroying 35 the surface of the shell, or marring or destroying the nature of the slot.

This attachment may be easily manufactured, readily placed upon the name plate and the assembly readily attached to the shell, 40 and at the minimum of expense.

We desire to comprehend within our invention such modifications as may be clearly embraced within our claims and the scope of our invention.

45 Having thus fully described our invention, what we claim is new and desire to secure by Letters Patent, is:

1. In the method of attaching a name plate to a shell, the formation of a lug on said 50 plate, inserting said lug through a slot in said shell of substantially the same dimensions in cross section as the lug and twisting the end of said lug to bring the cross sectional area of the lug across said slot and in engagement 55 with the edges of said slot whereby the name plate is drawn to and held on the shell.

2. In the method of attaching a name plate to a shell, forming a plate of metal and striking up therefrom a lug, attaching said plate 60 to a name plate, forming in said shell a slot, inserting said lug through said slot and twisting the end of the lug adjacent the slot to engage over the edges of the slot with the cross sectional area of said lug across the slot 65 and in engagement with the edges of said

slot whereby the name plate is drawn to and held on the shell.

3. In combination with a shell having a slot therein, a name plate, a plate having a lug struckup therefrom attached to said name plate, said lug extending through and closely fitting in said slot, and a twist on the end of said lug engaging the shell whereby the name plate is drawn to and held on the shell. 70

4. In combination with a shell having a slot therein with the material adjacent the slot drawn backwards, a name plate having a lug thereon extending through said slot, and means on said lug engaging the drawn-back edges of said slot to hold the name plate 80 on the shell.

5. In combination with a shell having a slot therein with the material adjacent the slot drawn backwards, a name plate, a plate having a lug struckup therefrom attached to said name plate, said lug extending through said slot, and a twist on said lug adjacent said shell engaging the drawn-back edges of said slot to hold the name plate on the shell. 90

6. In combination with a shell having a slot therein, a name plate, a plate having a shouldered lug struckup therefrom attached to said name plate, said lug extending through said slot with the shoulder in engagement with the shell and the end distorted to engage the shell to hold the name plate on the shell. 95

7. In combination, a shell with an elongated slot, a name plate, an elongated attaching and aligning plate on said name plate having a lug closely fitting within said slot to attach and align the name plate, and a distorted end on said lug engaging said shell for drawing the name plate to the shell and fastening it without destroying the alignment thereof. 100

In testimony whereof, we affix our signatures.
